United States Patent Office

Des. 184,712
Patented Mar. 31, 1959

184,712

BILLFOLD

Herbert S. Chase, Woodmere, N.Y., assignor to Bernard Cahn Co., Inc., New York, N.Y.

Application October 27, 1958, Serial No. 53,158

Term of patent 7 years

(Cl. D87—3)

I claim:

The ornamental design for a billfold, substantially as shown.
